UNITED STATES PATENT OFFICE.

WILLIAM M. DAVIDSON, OF EASTVIEW, KENTUCKY, ASSIGNOR OF ONE-HALF TO
MARSHALL LEE JOHNSON, OF EASTVIEW, KENTUCKY.

COMBINATION TOOL.

Application filed January 17, 1924. Serial No. 686,842.

To all whom it may concern:

Be it known that I, WILLIAM M. DAVIDSON, a citizen of the United States, residing at Eastview, in the county of Hardin and State of Kentucky, have invented certain new and useful Improvements in Combination Tools; and I do declare the following to be a full, clear, and exact description of the invention, such as will enable others skilled in the art to which it appertains to make and use the same.

The present disclosure relates to combination tools; and it is the main object of the invention to provide a simple, inexpensive, and easily operated tool to effectively apply wire bands for securing automobile radiator and other hoses, for repairing broken handles, and generally for applying wire bands wherever their use is desirable.

Another object is to provide a device which will not only form a band from a wire bent into U-shape, but may be used for cutting off the ends of the wire and flattening the remaining wire ends against the work.

Still another object is to provide a tool in which two different work-producing devices are disposed at opposite ends of a shank, and a single manually operable member is movable along said shank and co-operable with both devices.

Yet another object is to provide an exceptionally efficient wire cutting or other jaw-equipped tool which is operated by movement of a member (preferably threaded) along a shank.

With the foregoing in view, the invention resides in the novel subject-matter herein-after described and claimed, the description being supplemented by the accompanying drawing.

Figure 1 is a perspective view of a tool constructed in accordance with the invention, showing the use of the same for applying a wire band; and

Fig. 2 is a plan view showing the manner of using the invention in cutting wire.

In the drawing above briefly described which illustrates the preferred form of construction, the numeral 1 designates a straight shank which in the present disclosure is threaded. Swiveled upon one end of the shank 1, I have illustrated a wire-anchoring head 2 whose front end is formed

with a transverse groove 3 to receive the connecting portion 4 of a piece of wire bent into U-shape, after the ends of the wire have been passed around an object to be banded, as illustrated in Fig. 1. A wire-stretching block 5 is shown threaded upon the shank 1, and this block is preferably provided with outstanding wings 6 which can be easily grasped by hand. What is normally the upper side of the block 5 is provided with a pair of tapered wire-anchoring studs 7, while the opposite side and the rear side of said block are formed with transverse V-shaped wire-holding grooves 8. After engaging the wire with the work as shown in Fig. 1, the end portions of said wire are engaged with the grooves 8 and anchored by bending them around the studs 7. Then by turning the shank 1 through the block 5, by means of a suitable operating handle 9 provided for that purpose, it will be seen that the wire will be tightly stretched around the work. Then the entire tool may be swung upwardly to bend the end portions of the wire around the connecting portion 4 to anchor and complete the band. Then by turning the shank in the proper direction, the wire may be quickly loosened from the block 5. The construction described below may then be used for cutting off the end portions of the wire and flattening the remaining end portions around the connecting portion 4.

In the preferred form of construction, the handle 9 is in the form of a transverse head secured upon the end of the shank 1 remote from the head 2, and I have shown one end of this head provided with a jaw 10 which is co-operable with a movable jaw 11, this movable jaw being here shown as formed on one end of a pivoted operating arm 12, the pivot 13 of this arm being carried by the head 9. The arm 12 extends across the shank 1 in position to be operated by the block 5 when the latter is threaded in the proper direction along the shank, as will be clear by reference to Fig. 2. Preferably, a thrust collar 14 is loosely mounted upon the shank for interposition between the block 5 and the arm 12, when the latter is being operated. It will be seen that when a wire is positioned between the jaws 10 and 11 and the block 5 is threaded forcibly along the shank 1, the wire will be easily cut. Thus

the ends of the wire above referred to, may be cut simply by reversing the tool, after disconnecting it from the wire.

The end of the head 9, remote from the jaw 10, is preferably formed with a hammer head 15 which may be used in flattening the wire ends upon the work after the wire cutting operation is completed. In the construction shown, a narrow neck portion 16 connects the hammer head 15 with the remainder of the head 9, and the free end of the arm 12 is laterally curved as indicated at 17 to engage said neck, when said arm is folded against one side of the head 9 as shown in Fig. 1.

It will be seen from the foregoing that a simple and inexpensive, yet an efficient and easily operable tool, has been provided, and on account of the proven advantages of the details shown, they are preferably followed, but within the scope of the invention as

claimed, numerous changes may be made. Also, it will be seen that certain novel associations of parts are not necessarily restricted to use in connection with the other parts 25 herein disclosed.

I claim:

A wire banding tool comprising a threaded shank, a head swiveled on one end of said shank and having in its front end a 30 transverse groove to receive the connecting portion of a U-shaped piece of wire, and a wire-stretching block threaded on said shank and having a pair of wire-anchoring studs at one side, the opposite side and the 35 rear side of said block having transverse V-shaped wire-holding grooves in which the end portions of the wire are disposed before engaging them with said studs.

In testimony whereof I have hereunto af 40 fixed my signature.

WILLIAM M. DAVIDSON.
